UNITED STATES PATENT OFFICE.

NEWMAN H. HOLLAND, OF BROOKLINE, MASSACHUSETTS, ASSIGNOR OF
ONE-HALF TO CHARLES W. HOLTZER, OF BROOKLINE, MASSACHU-
SETTS.

TELEPHONE-EXCHANGE.

SPECIFICATION forming part of Letters Patent No. 694,918, dated March 4, 1902.

Application filed February 23, 1901. Serial No. 48,566. (No model.)

To all whom it may concern:

Be it known that I, NEWMAN H. HOLLAND, a citizen of Canada, residing in Brookline, county of Norfolk, and State of Massachusetts, 5 have invented an Improvement in Telephone-Exchanges, of which the following description, in connection with the accompanying drawings, is a specification, like characters on the drawings representing like parts.

10 The present invention relates to a telephone central-office signaling device, the object of the invention being to provide each operator at the central office with an automatic signal which will indicate when a busy line is clear 15 in case a subscriber has called for connection with said line while it was connected elsewhere, the signal also being provided with means for indicating not only the line called for, but the line which has called for it. Assuming, for example, that a certain subscriber 20 wishes to be connected with a certain other subscriber whose line is found to be busy at the time and also expresses a desire to be connected with said busy line as soon as it is disengaged, the operator at the central office can 25 connect the line called for with a signaling device which will not actually operate until the said line is disengaged, the device being also provided with means for indicating after 30 the signal is displayed the line of the calling subscriber who asked for the connection.

The invention is applicable to any existing telephone system and may be operated through the agency of the ordinary cord connections 35 in conjunction with a suitable table key or switch which will connect the circuit of the said signal into the line, so as to be properly operated, or through the agency of a special cord-circuit without the intervention of any switch. By utilizing cord-circuits in this 40 way the plugs serve as indicators to show the line wishing connection and the line with which connection is desired, and, furthermore, both lines are in this way connected with the 45 signaling device, so that if the calling-line while the subscriber is waiting for the line originally called for has obtained connection elsewhere the signal will not be displayed even when the called line is free. While not 50 essential, this is an important feature of the invention, since the signal will not be dis-

played until both lines are free, and the operator has nothing to remember, as the plug indicates which line they are.

In a multiple switchboard each operator is 55 provided at her own board with a certain number of answering-jacks, which represent the lines under her charge, and a complete set of calling-jacks, representing all the lines connected with the station, and the several calling-jacks of each line, which are distributed throughout the several operators' boards, are connected together and provided with a common ground connection. The several ground connections are for the purpose of completing a local circuit at the central office for various purposes in accordance with the system in use, as will be hereinafter fully described, and these ground connections are utilized in the present invention to close a circuit 60 through the special signaling device, which will remain closed so long as either of the lines which are waiting connection is in use. The special signaling-circuit is arranged to be connected either by the regular plugs or by special 65 plugs with a ground connection of its own, the jacks of each of the lines which are awaiting connection thus being grounded through the special signaling-circuit. If either of these lines, therefore, is connected with some 70 other line at any board, one terminal of the central-office battery is connected with the ground through the jack in which the plug belonging to that line is inserted, and as the other terminal of the central-office battery is 75 grounded it is obvious that a circuit will be completed through the said signaling device until the said line is disconnected by the removal of the plug. The signaling device is 80 preferably arranged in a closed circuit, in which case it is adapted to be displayed when the said closed circuit is broken, which will 85 only occur when both of the connected lines are disengaged.

It is to be understood, of course, that the term "ground" is used as indicating a common return-circuit, which under the existing conditions is usually metallic, but is more conveniently illustrated as a "ground," this term being commonly used for convenience 90 with this significance and conventionally illustrated in the drawings. It should be further

understood that while this special signaling device may be more conveniently arranged in a closed circuit it is not necessarily so arranged, as an open circuit could be employed 5 which would be closed on the removal of the plug from the jack of the line with which connection is desired.

Figure 1 is a diagram of these telephone-stations operated on the local-battery system, 10 showing the connections at the central office, so far as they relate to the present invention; Fig. 2, a similar diagram showing the invention embodied in the common-battery system; Figs. 3 and 4, details to be hereinafter 15 referred to.

Referring to Fig. 1, which illustrates a practical device embodying the invention as applied to the system in which local magnetos are employed for signaling purposes and in 20 which the ordinary cord-circuit is utilized in conjunction with a suitable table key or switch to operate the special signal, it may be assumed that station 241 is connected with station 1409 and that station 411 has asked for 25 connection with station 241, for example, and has been informed that the said station 241 is connected with another station or "busy," as is shown in the drawings. Under these 30 circumstances the operator will place one of the plugs a of a cord-circuit in the answering-jack b of station 411 and the other plug a^2 of the same cord-circuit in the calling-jack b^2 of station 241, which is located at her own board, at the same time manipulating the table-key 35 c , which forms part of the special signaling system embodying the present invention. The said table-key is so arranged as to open the circuit of the tip-wire a^{10} , (normally closed through contact member c^2), so that when the 40 key is manipulated there is no outside connection between the two lines in the jacks of which the two plugs have been inserted, and the thimble-wire a^{12} by the same operation is connected through the switch member c^3 with 45 a wire a^{13} , which passes through the special signaling-magnet h to the ground G . The thimble of the jack b^2 of the busy line as well as the thimble of the jack b of the waiting line are therefore both connected with the 50 ground, and as all the thimbles belonging, respectively, to said lines are connected together it follows that every thimble belonging to either line is grounded. When the table-key is in normal position, as when two lines 55 are connected together for conversation, the tip-wires a^{10} are connected through the switch member c^2 , and the thimble-wires a^{12} , instead of being ground, are connected through the switch member c^3 with a wire a^{14} , leading to 60 one terminal of the battery D , the other terminal of which is grounded. If, therefore, any two stations are connected together and the other cord-circuit (in which the table-key 65 has been turned, as shown at the right-hand side of Fig. 1) has one of its plugs in any jack on either of the connected lines, there will be a closed circuit starting from the bat-

tery D and passing through conductor a^{14} , switch member c^3 , conductor a^{12} to the thimble of one of the jacks b^2 , from which it passes 70 to the thimble of the jack b^2 in which the other cord-circuit has been inserted, thence through the wire a^{12} , switch member c^3 , wire a^{13} , electromagnet h to ground G and back to the battery. Said electromagnet h therefore 75 will be energized so long as the line which is wanted remains busy, but will be deenergized as soon as the active plug has been removed, no matter at what part of the multiple 80 switchboard the said active plug has been inserted.

The electromagnet h , above referred to, is shown as having an armature h^2 , adapted to control a drop h^3 , which makes contact with the terminal of a special signaling-circuit 20 85 22 through a local battery 21 and a lamp 23, the other terminal of said circuit being arranged to make contact with the armature h^2 when the said armature is restored to normal by the deenergizing of the magnet h . If the said magnet is deenergized, a portion of the armature h^2 will make contact with said terminal, closing the circuit through the magnet-frame and lighting the lamp 23, which constitutes the said special signal. This will only happen 90 when all the plugs which may have been connected with any of the jacks of station 241 are removed, because as long as any plug is in any jack of said station at any board there will be a complete circuit energized by the 100 battery D through the magnet h . Consequently so long as the station 241 is connected with any other station on the line the signal 23 will not be displayed, but as soon as the said station 241 is disconnected the said 105 signal will be displayed and the operator at the central office will be informed that line 241 is free. Having previously inserted the plug a in the answering-jack of line 411, which desires connection with station 241, the 110 other plug of the same cord-circuit being already inserted in one of the calling-jacks of station 241, it is only necessary to release the table-key c and send a signaling impulse 115 over the line, which will call the subscribers at stations 241 and 411, which stations are already connected by the cord-circuit.

In the diagram the several jacks, only three of which are shown as corresponding to each station, are apparently on the same board; but it is to be understood that there are a large number of the calling-jacks distributed throughout the central station, each operator's board containing one only besides the answering-jack, and that the plug a , which is shown in jack b^2 of station 241, may be at a board remote from that in which the cord-circuit containing the special signal is located, so that the operator at the said board has no means for knowing whether station 125 241 is connected with any other station or not, except through the special signal described. It may happen that the busy line 130 called for is connected at the operator's own

board, in which case the calling-jack at the said board is not available for the plug of the cord-circuit which is to control the signal. In view of this fact it is well to provide each operator with one special cord-circuit having a plug adapted to fit over and make contact with the ordinary plug, as indicated in Fig. 3, the said plug being indicated by the reference-letter A and having a contact-piece A², adapted to make contact with the sleeve-wire terminal of the ordinary plug in order to obtain the ground connection to complete the circuit for the special signal.

15 The cord-circuit which connects station 241 with station 411 is shown as provided with the same signaling apparatus as that which has been described in detail, and for convenience a battery is shown in each one of the said 20 cord-circuits, each battery having a ground-terminal. As a matter of fact a common battery would be used for all the cord-circuits, and the same battery may conveniently be employed for this purpose as is now employed.

25 for the busy test, although this is obviously not essential. In the construction hereinbefore described, however, each cord-circuit at any one operator's board is provided with a special table-key and a special signal 23, and

30 when the operator is asked for connection with a line which proves to be busy she connects the two lines in the ordinary way with any cord-circuit which may be at her command, but operates the table-key belonging 35 to the said cord-circuit which places the special signal in circuit as described, so that as soon as said signal is displayed she is made aware of the fact that the two lines which the calling subscriber has wished to have connected are free to be connected and she acts 40 accordingly, restoring the conditions to normal by the manipulation of the table-key—that is, the restoring of the said table-key to its normal condition.

45 In the particular system thus far described the special signal 23 is included in a local-battery circuit which must be closed only when the current ceases to flow through the cord-circuit which indicates the two stations which

50 are waiting to be connected together. It is necessary, therefore, that the said circuit should be normally open and that when the signal is to be used it should be placed in condition to be finally closed, but that it should

55 not be closed until the signal is to be displayed. A simple expedient for accomplishing this result is herein shown, the armature h² of the magnet h being arranged to support a drop h³, which falls into contact with one

60 end of a special-battery circuit when the magnet h is energized, the said drop being held up by the armature of said magnet when in its normal position. The lifting of the armature, however, pulls the said armature out

65 of contact with the opposite end of said circuit, so that the circuit is still open, one end thereof, however, being connected with the

magnet-frame by the drop which has been previously released. As soon as the magnet becomes deenergized by the removal of the plug from the busy line the armature drops, coming into contact with the other end of the local circuit and completing the same through the magnet-frame, so that the signal is displayed, as by the lighting of the lamp 23. 75

The foregoing description has been directed specifically to the construction shown in the drawings in order that the invention may be clearly comprehended, with the understanding, however, that such specific arrangement is not by any means essential, since various means may be devised for controlling a signal through the agency of the cord-circuit which connects two lines in use and a cord-circuit connecting the two lines which are 85 waiting. It will be seen, however, that in any of such arrangements so long as a station with which connection is desired is connected at any point in the multiple switchboard with any other station the said signal-circuit will 90 be controlled by any plug in any of the jacks belonging to the said station and that the signal will not be displayed so long as the said line is connected at any point in the central office. 95

In order to further illustrate the adaptability of the invention to any existing system and also to illustrate a modification in the arrangement of the special signal at the central office, the invention is shown in Fig. 2 as applied to the so-called "central-energy" or "common-battery" system, and the special signal is included in a special cord-circuit instead of in each of the regular cord-circuits combined with a special controlling device or table-key, as hereinbefore described. In the central-energy system all the jacks belonging to the same line are connected together and grounded, so as to receive current from the battery at the central office whenever a connecting cord-circuit is in one of the jacks, the said battery thus not only serving to operate the busy test, but also commonly serving to energize a special electromagnet when the lines are in use in order to cut out the permanent signaling battery which is on the line all the time, but open-circuited by the condenser except when a signal is being sent in. Referring to Fig. 2, in which the same reference-letters will be used, so far as possible, as those already used in Fig. 1 to identify analogous parts, it may be assumed that station 241 is connected with station 1409 through the usual cord-circuit having the plugs a and a² inserted in the jacks b² belonging to the two stations, respectively. The usual clearing-out signal or ring-off drop-circuit is illustrated, but need not be described in detail, since it forms no part of the present invention. It will be seen, however, by tracing the circuits that so long as any plug a stands in any jack b² of station 241 one terminal of the battery D will be connected through conductors a¹⁴, a¹², a¹²¹, a¹²², and a¹²³. 110 115 120 125 130

with the thimble of the jack b^2 of said station 241, which thimble has a permanent connection with the ground G. In the construction shown the special signal 23 is controlled by 5 an electromagnet h, one terminal of which is permanently connected with the ground at G, the other terminal being connected with both wires of a special cord-circuit e, having two plugs e^2 , which are adapted to be inserted 10 and, respectively, in the answering-jack b of the line which desires connection and any calling-jack b^2 of the line which is found to be busy, in this case the line belonging to station 241. The said cord-circuit thus indicates to the operator at the central office the 15 two lines which desire connection and so long as either of the said lines is busy, so that any of the thimbles belonging to the said line is connected with the battery D, current will 20 flow from the battery D over the circuit above traced, part going to ground over one member or the other of the said cord-circuit e and through the electromagnet h. In Fig. 2 only two jacks are shown as belonging to 25 each station, and it may be assumed that the jacks shown as belonging to station 241 are both calling-jacks, the answering-jack being omitted. At station 411, however, the jack b is supposed to be the answering-jack 30 belonging to said station and located at the board of the operator who has received the call, as this is the jack in which she would place the special plug as an indicator, the other plug being placed in that one of the 35 calling-jacks belonging to the station desired which is located at the same board. In reading the diagram, therefore, it should be assumed that the answering-jack b belonging to the station 411 and the calling-jack 40 b^2 in which plugs e^2 are inserted are located at the same board and that the jack b^2 in which plug a is inserted is at another board, the said jacks being connected together, however, by the conductor a^{124} . The signal 23 is 45 shown as included in a circuit 20 to 22, having a local battery 21, the said circuit being adapted to be closed, as illustrated, when the armature of the electromagnet h is released, the said armature acting upon a contact-piece 24. The current will continue to flow 50 through the electromagnet h so long as any thimble belonging to either of the lines which are waiting to be connected has the plug of a cord-circuit connected therewith, and the signal 23 will not be displayed until both of the lines in question are clear. Upon the display of the signal the position of the plugs e^2 of the special cord-circuit e indicates to the 55 operator the two lines which desire connection, and the special cord-circuit can then be replaced by one of the regular cord-circuits to connect the two lines together. In order to prevent the display of the signal 23 when the cord-circuits are not in use, the electromagnet h is adapted to be energized by a local battery H, one terminal of which is connected 60 with each member of the special cord-circuit

e and the other terminal of which is connected to a plate H^2 , upon which the metallic contacts e^3 of the plugs e^2 rest when the cord-circuit is not in use, thus completing the battery-circuit and maintaining the electromagnet energized. So long, therefore, as either of the plugs e^2 rests upon the plate H^2 the signal 23 will not be displayed, and as soon as 70 either plug is connected with the thimble of the busy line the electromagnet h will be placed in circuit with the battery D, so that the signal 23 will not be displayed at any time except when it has been placed in condition to indicate that a busy line in which 75 connection is desired has become free. In the case of party-lines the cord-circuit which is utilized for the special signal (or every cord-circuit when table-keys are used) may 80 be provided with an indicator 1, as shown in Fig. 4, which can be turned or otherwise manipulated after the plugs are in place in order to show which party on the line is awaiting 85 connection.

In the foregoing description the systems which have been chosen to illustrate the invention have been described in detail in order that the invention may be clearly understood. It is obvious, however, that the specific construction shown is not essential to the invention, the problem being merely to provide the operator at the central office with a special signal which can be tapped onto a busy line, so as to be displayed when the said 90 line is free, accompanied by any suitable means for indicating the line which has previously called for the busy line and wishes connection therewith as early as possible. It is essential only that the said signal should 95 be controlled in such a manner as to be displayed only when there are no plugs in any of the jacks belonging to the line which has been found to be busy and that any kind of 100 indicator might be used to inform the operator which line is to be connected when the busy line becomes free. The use of the plug connected with the said circuit, however, as an indicator is not only a convenient way for 105 indicating the calling-line, but possesses a 110 further important advantage in that it places the calling-line also in connection with the special signaling-circuit, so that if the said calling-line after it has sent in the call and before the busy line has become free has been 115 connected with another line at some other part of the board the signal will be controlled by the said calling-line and will not be displayed until both of the lines desiring connection are free. It is not, however, intended 120 to limit the invention in this respect, since it is believed to be broadly new to provide the central-office system with a special signal adapted to be connected with a busy line and to be displayed when said busy line is free, 125 combined with any means for indicating to the operator at the central office the calling-line which desires connection with the busy line at the earliest possible moment.

While, as has been stated, the busy-test battery may conveniently be employed for the purpose of actuating the special signal, the common busy test must not be confused with the invention, for the reason that, assuming, for example, that the operator at central were to keep a memorandum of calling-lines and the lines with which connection is desired, she could only ascertain if the busy lines had become free by applying the busy test from time to time, and connections might be and probably would be made between times, so that the operator of the central office would be in exactly the same position in which a subscriber is placed who repeatedly calls for a given line and is unfortunate enough to call each time just after a connection has been made elsewhere. In accordance with the invention, on the other hand, as soon as the special circuit has been connected with the busy line and the indicator placed in position, these operations entailing substantially no additional work on the part of the operator, there is nothing more to be done, as the display of the signal will call the operator's attention to the fact that the lines wish connection and are both free, and the indicator and circuit connection impart the desired information as to which lines are to be connected. Furthermore, the signal embodying the invention should not be confused with the ring-off drop or clearing-out signal, as this signal imparts no information except at the board where connection has been made, while the subscriber desiring connection may be in charge of another operator. Furthermore, even if all three subscribers are connected with one board the clearing-out signal affords no indication of the line which has been unable to get connection.

I claim—

1. In a telephone system, electrically-connected jacks for each incoming line; cord conductors for connecting a jack of one line to a jack of another line to establish communication; a signaling device; a controlling device for preventing the operation of said signaling device while two lines are connected for communication; a special circuit for said controlling device; means for connecting one terminal of said special circuit with one terminal of any jack; and a terminal of one conductor of each set of cord conductors co-operating with the jack-terminal aforesaid, the said conductor being normally connected with the other terminal of said special circuit whereby the completion of said circuit depends upon the connection between the connecting cord-conductor set and a jack connected with the jack which has been connected with said special circuit.

2. The combination with the sets of connecting cord conductors each of which has one of its conductors provided with a contact-piece connected with one terminal of a battery; of the jacks for the incoming lines, each having a contact for connection with the said

contact-piece, the several jacks for the same line being connected together electrically; a special signal; a controlling-circuit for said special signal, one end of which is connected with the opposite terminal of said battery; and means for connecting the other end of said controlling-circuit with any of the jack-contacts aforesaid, the said controlling-circuit being arranged to prevent the operation of the signal while two lines are connected. 70

3. In a telephone system, the combination with the several electrically-connected sets of jacks belonging respectively to the several lines; of the sets of cord conductors, each of which has one of its conductors connected with one terminal of a battery, said conductor being provided with a contact-piece to make contact with any jack; a special circuit 80 having a connection with the opposite terminal of the battery aforesaid and means for connecting the said special circuit with any jack; and a signal controlled by said circuit, said circuit being arranged to prevent the operation of said signal while two lines are connected for communication. 85

4. In a telephone system the combination with means for connecting two lines for communication; of a special conductor adapted 95 to connect one contact of a jack of a calling-line with one contact of a jack of a busy-line without connecting the other contacts of said jacks to establish communication between said lines; a source of current one terminal 100 of which is connected with said busy-line-jack contact, the other terminal being connected with said special conductor; a special signal controlled by said source of current; and means for preventing the operation of said signal consisting of a circuit controlled by the means for connecting two lines for communication. 105

5. In a telephone system, a special signal; a circuit controlling said signal, one terminal 110 of which is adapted to be connected to one contact member of any jack, the other terminal being connected with one terminal of a battery; electrically-connected jacks for each incoming line; conductors for connecting one 115 line with another, one member of each set of cord conductors being normally connected with the other terminal of said battery; a contact-piece for said member adapted to make contact with that member of the jack which is connected with the battery-terminal whereby the circuit for the special signal is controlled; and means for indicating the line to which said special signal refers. 120

6. In a telephone signaling system, a special signal for the purpose described; a circuit for controlling said signal; sets of conductors, one conductor of each set having one terminal adapted to be connected with one terminal of said circuit; jacks having co-operating terminals; means for connecting said jack-terminals to the other terminal of said circuit; and means for indicating the line awaiting connection, as set forth. 125 130

7. In a telephone system a set of conductors adapted to connect the jacks of two telephone-lines; and a special signal controlled by said set of conductors in conjunction with 5 a set of conductors connecting either of said two lines with a third line, the circuit controlling said signal, being arranged to prevent the operation of said signal while said telephone-lines are connected for communication.
10. 8. In a telephone-exchange system, the combination with the incoming lines and their jacks; of sets of conductors coöperating with said jacks to connect two lines for purposes of communication; a special conductor adapted to connect one terminal of a jack of a calling-line with one terminal of a jack of a busy line; a special signal; and a circuit for said special signal controlled jointly by the conductors aforesaid, substantially as described.
15. 9. In a telephone system, the combination 20 with central exchange apparatus; of a special signal; a cord-circuit for connecting two lines for communication; a special local circuit for controlling said special signal, one terminal of said circuit being connected with one member of said cord-circuit; means for connecting the other terminal of said circuit with a jack of a busy line, whereby a signal is displayed when the two connected lines are disconnected; and means for indicating the waiting line to which said signal relates.

In testimony whereof I have signed my name to this specification in the presence of two subscribing witnesses.
